UNITED STATES PATENT OFFICE.

RICHARD GRIST AND DÉSIRÉ PATIN, OF PHILADELPHIA, PENNSYLVANIA,
ASSIGNORS OF ONE-THIRD TO ROBERT GRIST, OF SAME PLACE.

SHOE.

SPECIFIC VISION forming part of Letters Patent No. 286,129, dated October 2, 1883.

Application filed June 7, 1883. (No model.)

To all whom it may concern:

Be it known that we, RICHARD GRIST and DÉSIRÉ PATIN, citizens of the United States, residing at Philadelphia, in the county of Philadelphia and State of Pennsylvania, have invented certain new and useful Improvements in Shoes, of which the following is a specification, reference being had therein to the accompanying drawings.

10 Our invention relates to an improvement in shoes; and it consists in a gaiter or shoe of which the vamp is cut with flaps, in imitation of a Newport tie, said flaps being located at the lower part of the quarter, across the ball 15 of the foot, whereby a shoe is produced combining the advantages of a gaiter and a Newport tie, as will be more fully described hereinafter.

In the accompanying drawings, Figures 1 20 and 2 are perspective views, showing our invention and a modification thereof. Figs. 3 and 4 are detail views of the vamps.

25 A represents the shoe, having the vamp B, which is provided with flaps C, as shown, these flaps being located at the lower part of the quarter. In order to enable the shoe to be loosened or tightened at will, we provide ribbons or buckles D with the flaps, which enable them to be adjusted so as to cause the shoe

to conform to the size and shape of the foot of the wearer, and to enable it to be loosened, should the foot swell, thus insuring ease and comfort to the wearer. A shoe thus constructed presents an elegant appearance, and but little is added to the cost of it over the shoes now in common use.

We do not limit ourselves to the particular form of the cut of the vamps shown in the drawings hereto annexed, as it is obvious that many modifications may be made therein without departing from the spirit of our invention.

Having thus described our invention, we claim—

A shoe or gaiter having its quarters laced in front and provided with a vamp having the flaps C across the ball of the foot, the flaps being made to project from the vamp at the lower end of the laced portion, and connected together by means of suitable fastening devices, substantially as shown and described.

In testimony whereof we affix our signatures in presence of two witnesses.

RICHARD GRIST.
DÉSIRÉ PATIN.
